[57] CLAIM

The ornamental design for a fishing pole light, as shown and described.

DESCRIPTION

FIG. 1 is a front elevational view of a fishing pole light showing my new design;

FIG. 2 is a rear elevational view thereof;

FIG. 3 is a left side elevational view thereof; and,

FIG. 4 is a right side elevational view thereof.
The broken lines are shown for illustrative purposes only and form no part of the claimed design.
